UNITED STATES PATENT OFFICE.

CHRISTIAN AUGUSTUS ALBRECHT, OF BERLIN, GERMANY, ASSIGNOR TO MERGEN-THALEER LINOTYPE COMPANY, A CORPORATION OF NEW YORK.

DISTRIBUTING MECHANISM OF TYPOGRAPHICAL COMPOSING-MACHINES.

1,142,222.

Specification of Letters Patent.

Patented June 8, 1915.

Application filed March 29, 1915. Serial No. 17,905.

To all whom it may concern:

Be it known that I, CHRISTIAN AUGUSTUS ALBRECHT, a citizen of the United States of America, at present residing at Chausseestrasse 23, Berlin, N. 4, in the Empire of Germany, have invented new and useful Improvements in the Distributing Mechanism of Typographical Composing-Machines, of which the following is a specification.

This invention relates to typographical composing machines such as those known commercially under the trade mark "Linotype," and particularly those which are provided with several magazines, and in which are used matrices having font-distinguishing notches in their feet. In such machines, the matrices, when entering the distributor, pass over font-distinguishing bridges or the like, which, acting in conjunction with the font-distinguishing notches on the matrices and the gaps in the ribs on the distributor rail, effect, in the well known manner, the distribution of those matrices to the particular magazines appropriate to the font to which they belong.

In accordance with hitherto known arrangements, the matrices are propelled along the distributor rail and over the font-distinguishing bridges, by three distributor screws which engage with three of the four ears of each matrix, namely, the two upper ears and one of the lower ones, with the result that the matrices, when supported only by the font distinguishing bridges, have a tendency to assume an oblique position and so render accurate distribution uncertain. The provision of a fourth distributor screw of ordinary construction for the purpose of overcoming this difficulty is impracticable, because the distance between the two lower screws would leave too little room for the matrices to pass freely when falling from the distributor.

According to the present invention, the above-mentioned defect is remedied by providing a fourth distributor screw which operates on the second lower ear of each matrix while it is being propelled over the font-distinguishing bridges, and which is gapped or mutilated over those portions of it which coincide with the spaces between the font-distinguishing bridges so that the descent of the matrices from the distributor at those places is not impeded.

The accompanying drawings illustrate a constructional form of the invention so applied to the font-separator of a machine provided with four magazines, Figure 1 being a vertical cross-section of the distributor, 60 and Fig. 2 an elevation of the same as seen from the right of Fig. 1, that is to say from the back of the machine.

The matrices 1 are successively raised by the lifter 2 and pushed over the guide rails 3 so that they engage with the distributor screws 4, 5, 6, which carry them on to and along the first (7) of the font-distinguishing bridges 7, 8, 9 and 10. When the position of the font-distinguishing notches 11 in the feet of the matrices, does not coincide with that of the ridges on the bridge 7, the matrices will be supported by those ridges at such a height as will enable them to be engaged by the ribs on the distributor rail 12 70 by which they will be supported while passing over the chute 13 on their way to the bridge 8. When, however, as shown in Fig. 1, the notches 11 are coincident with the ridges on the bridge 7, the matrices will not 80 engage with the ribs on the rail 12 and, when propelled by the screws beyond that bridge, will fall into the chute 13. A gap in the ribs on the distributor rail 12, situated above each of the bridges 8, 9 and 10, enables a similar distributing operation to be carried out by each of those bridges, so that all the matrices are delivered to the respective chute 13, 14, 15 or 16 by which they are 85 conveyed to the distributor appropriate to 90 the particular font to which the matrix belongs. All the devices just described are constructed as heretofore, and operate in the known manner.

In order to prevent the matrices assuming, as above-mentioned, an oblique position while passing over the bridges 7, 8, 9 and 10 the present invention provides a fourth distributor screw 17. The shaft of this screw 17 is of smaller diameter than the shafts 100 of the other three screws, and it is provided with a mutilated thread, which engages the second lower ear of each matrix during its passage over either of the font-distinguishing bridges, but is discontinued over the respective chutes 13, 14, 15 and 16, so as to present no obstacle to the free passage of the matrices into those chutes. As soon as the matrices leave the guide rails 3, they are engaged by the first portion 18 of the screw 17, 110

as well as by the screws 4, 5 and 6, and the matrices remain under the control of all four screws until they reach the end of the bridge 7, where the said portion 18 of the screw 17 ceases, and any matrix which has not been engaged by the distributor rail 12, is free to drop into the chute 13, there being no thread present at that part of the screw 17 to interfere with such dropping, and the diameter 10 of the shaft of that screw being small enough to allow the falling matrix to pass freely between it and the screw 6. Matrices which have been engaged by the distributor rail 8 during their passage over the bridge 7, are 15 propelled over the chute 13 by the three screws 4, 5 and 6, until, just before arriving over the second font-distinguishing bridge 8, the second portion 19 of the screw 17 comes into engagement with the second lower ear 20 of each matrix, which thereafter traverses the bridge 8 under the control of all four screws. This second portion 19 of the screw 17 ceases at the end of the bridge 8, and consequently all matrices released from the 25 distributor rail 12 during their passage over the bridge 8 are free to drop into the chute 14, matrices which have not been so released continuing their travel, under the control of the three screws 4, 5 and 6, towards the next 30 font-distinguishing bridge 9. While the matrices are passing over the bridges 9 and 10, the third and fourth portions 20, 21, of the screw 17 come into operation in the same manner as that just described with reference 35 to the portions 18 and 19.

It is to be understood that, although the invention is herein described and illustrated as applied to a so-called font-separator, it may be equally well employed in connection 40 with distributing mechanism which separates the matrices according to character.

Having described my invention, I declare that what I claim and desire to secure by Letters Patent is:—

45 1. In a typographical composing machine, the combination with a distributor rail and three distributor screws adapted to propel matrices along the said rail, of a fourth distributor screw also adapted to propel matrices along that rail and having its thread mutilated or gapped in the direction of its length.

50 2. In a typographical composing machine, the combination with a distributor rail adapted to support and release matrices at respectively different parts of its length, chutes adapted to receive matrices released from the distributor rail, two distributor screws adapted to engage the upper ears of a 55 matrix and a third distributor screw adapted

to engage one of the lower ears of such matrix, of a fourth distributor screw adapted to engage the other lower ear of that matrix and having gaps or mutilations in its thread located above the said chutes. 65

3. In a typographical composing machine, the combination with a distributor rail adapted to support and release matrices at respectively different parts of its length, font-distinguishing bridges adapted to support matrices released from the distributor rail, two distributor screws adapted to engage the upper ears of a matrix and a third distributor screw adapted to engage one of the lower ears of such matrix to propel it 70 along the said rail and over the said bridges, of a fourth distributor screw adapted to engage the other lower ear of that matrix and having its thread divided by gaps or mutilations into a number of parts corresponding 75 with the number of bridges, each such part terminating in the direction of travel of the matrices in the same vertical plane as does the adjacent bridge.

4. In a typographical composing machine, 80 the combination with a distributor rail adapted to support and release matrices at respectively different parts of its length, font-distinguishing bridges adapted to support matrices released from the distributor rail, chutes adapted to receive matrices falling off the bridges, two distributor screws adapted to engage the upper ears of a matrix and a third distributor screw adapted to engage one of the lower ears of such matrix, 85 of a fourth distributor screw adapted to engage the other lower ear of that matrix and having gaps in its thread located above the said chutes. 90

5. In a typographical composing machine, 100 the combination with a distributor rail adapted to support matrices, a font distinguishing bridge adapted to deliver matrices of different fonts to the said rail and into a chute respectively, the said chute, two 105 distributor screws adapted to engage the upper ears of a matrix and a third distributor screw adapted to engage one of the lower ears of that matrix to propel it over and beyond the said bridge, of a fourth distributor 110 screw adapted to engage the other lower ear of that matrix, and terminating in the direction of travel of the matrices in the same vertical plane as does the bridge. 115

In witness whereof I have hereunto set my hand in the presence of two witnesses.

CHRISTIAN AUGUSTUS ALBRECHT.
